UNITED STATES PATENT OFFICE.

ÁRPÁD KASZTRINER, OF SÁTORALJA-UJHELY, AUSTRIA-HUNGARY.

COUCH FOR USE ON THE WATER.

1,002,701.

Specification of Letters Patent. Patented Sept. 5, 1911.

Application filed February 13, 1911. Serial No. 608,309.

To all whom it may concern:

Be it known that I, ÁRPÁD KASZTRINER, physician, subject of the King of Hungary, and residing at Sátoralja-Ujhely, in the 5 Kingdom of Austria-Hungary, have invented a new and useful Couch for Use on the Water; and I do hereby declare the following to be a full, clear, and exact description of the same.

10 It is often desirable for medical reasons or for the sake of comfort or convenience that bathers or invalids undergoing a water cure should be able to remain resting on the surface of the water in a recumbent position during a protracted period. Appliances for this purpose have hitherto been complicated and therefore costly.

Now this invention has for its object to provide an improved floating couch composed of bamboo or other suitable material rendered buoyant by means of air tubes so that it will be supported on the surface of the water in such a manner as to enable the person lying on it to be subjected to convenient and undisturbed medical treatment.

20 The improved floating couch consists substantially of three portions jointed to one another so as to be capable of being folded together. Each portion consists of netting 30 stretched across a frame of bamboo. The outer or end frames are jointed to the middle frame in such a manner as to fold inward in opposite directions and are connected to each other positively by means of 35 cords so that when the frame that supports the legs or feet of the patient is depressed the frame that supports the head of the patient will be raised.

One construction of the improved couch 40 is illustrated by way of example in the accompanying drawings in which:

Figure 1 is a side view of the couch with its parts in one position, and Fig. 2 is a side view of the couch with its parts in another position, Fig. 3 is a top view of the couch, and Fig. 4 is a vertical cross section on the lines A—B of Fig. 3.

45 The improved couch consists of three frames 1, 2, 3, of bamboo or other suitable material with netting stretched across or between the sides or ends of each frame. These frames 1, 2, 3, are designed to support respectively the head, body and legs of the person resting on the couch, and are jointed or hinged to one another so that the frame 1 50 can fold over the frame 2, and the frame 3,

can fold under the frame 2. The abutting ends of the frames 1 and 2 are arranged to meet at an angle as indicated at 4 in Fig. 1, in order that the frame 1 shall be inclined 60 at a small upward angle when in its position of use. A bolt 6 slidable in a socket 5 is provided for the purpose of fixing the frame 3 in the horizontal position. An air tube or float 7 is provided capable of being slid 65 in the usual manner on cords along the underside of the frame 1. This air tube and the side air tubes hereinafter described serve to support the couch with the person resting thereon on the surface of the water. An air 70 cushion 8 serving as a head rest is attached to the upper side of the frame 1. The frame 1 is made narrower than the middle frame 2 so that it can fold inside the frame 2. Side supports 9 of oblique parallelogram form 75 are attached to both longitudinal sides of the middle frame 2; they inclose the air tubes 10 that support the couch with the air tubes 7 arranged under the head frame, upon the surface of the water. A cord 11 80 attached to the outer end of the frame 1, passes over pulleys 12 mounted on the side supports 9, and is attached at its other end to the outer end of the frame 3. By this means the frames 1 and 3 are connected positively together so that when the fastening 85 5, 6 has been undone, the frame 1 is raised at an angle when the frame 3 is depressed. The transverse rod 13 connecting the sides of the middle frame 2 together, which is 90 situated nearest the frame 1, is bent or curved so as to allow a person to lie or sit with comfort on the couch. The side support is connected to the transverse connecting rods by means of bent or curved 95 supporting bars 14 (Fig. 4).

In use the couch assumes the position shown in Fig. 1.

In its folded position, the frame 1 lying upon the frame 2, and the frame 3 (after 100 the bolt fastening 5, 6 is undone) lying under the frame 2, the couch takes up very little space and can be very easily transported.

The couch may be provided with oars or 105 paddles not shown, for the purpose of executing slight movements on the water.

I declare that what I claim is:—

1. In a floating couch as set forth, a head supporting frame, a legs supporting frame, 110 a middle frame, rollers mounted on the side supports of the middle frame, cords passing

over the said rollers and connecting together positively the head supporting frame and the legs supporting frame and providing means by which on the user depressing 5 the legs frame, the head supporting frame will be elevated.

2. In a floating couch as set forth, a middle frame, a head supporting frame, a legs supporting frame and means adapted to 10 raise the head supporting frame and depress the legs frame, a float arranged under the head supporting frame and slidable along the underside of said frame.
3. In a floating couch as set forth, a middle frame, a head supporting frame and a legs supporting frame, air tubes, a float, 15 slidable along the underside of the said

frame and adapted to support the frames on the water.

4. In a floating couch supporting bathers and invalids in the water, the combination of network covered flexibly connected bamboo frames, means providing the necessary buoyancy, and means for elevating to any desired angle the head frame and depressing 25 the legs frame as herein set forth.

In witness whereof I have hereunto signed my name this 30th day of January, 1911, in the presence of two subscribing witnesses.

ÁRPÁD KASZTRINER.
